UNITED STATES PATENT OFFICE.

BROR ADOLPH NYGREN, OF MINNEAPOLIS, MINNESOTA.

FOLDING UMBRELLA.

1,045,595.

Specification of Letters Patent. Patented Nov. 26, 1912.

Application filed March 16, 1912. Serial No. 684,102.

To all whom it may concern:

Be it known that I, BROR ADOLPH NYGREN, a citizen of the United States, residing at Minneapolis, in the county of Hennepin and State of Minnesota, have invented certain new and useful Improvements in Folding Umbrellas; and I do hereby declare the following to be a full, clear, and exact description of the invention, such as will enable others skilled in the art to which it appertains to make and use the same.

My invention has for its object to provide an improved folding umbrella and, to this end, it consists of the novel devices and combinations of devices, hereinafter described and defined in the claims.

The invention is illustrated in the accompanying drawings wherein like characters indicate like parts throughout the several views.

Referring to the drawings, Figure 1 is a view partly in side elevation and partly in section showing the improved umbrella in an open position, some parts being broken away and other parts removed; Fig. 2 is a view principally in longitudinal section taken centrally through the improved umbrella showing the same in a partly folded position; Fig. 3 is a detail view in section showing one of the locks for the cane sections; Fig. 4 is a view in longitudinal section, taken on the line $x^4 x^4$ of Fig. 1; Fig. 5 is a transverse section taken on the line $x^5 x^5$ of Fig. 4; Fig. 6 is a transverse section taken on the line $x^6 x^6$ of Fig. 3; and Fig. 7 is a detailed view showing one of the hinge connections between the outer and intermediate sections of the cover supporting ribs.

The cane of the improved umbrella is, as shown, preferably made up of three metallic sections that are indicated by the numerals 1, 2 and 3. These cane sections are telescopically mounted to slide one within the other, and are also preferably made square in cross section. The cane section 1, at its lower end, is provided with a hand piece 5. A spring latch 6 is rigidly secured within the cane section 1 near its inner end, and is provided with a cam head 7 that works within and is guided by a slot formed in said cane section. Formed in and near the outer end of the cane section 2 in a lock slot 8, arranged to register with and receive the cam head 7 of the latch 6 to lock the cane section 1 to the cane section 2 in its extended

position, and against endwise movement in either direction. Rigidly secured to the cane section 3 is a spring latch 9 having a cam head 10 that works within and is guided by a lock slot formed in said cane section near its lower end. Near the inner end of the cane section 2 is formed a slot 11, arranged to register with and receive the cam head 10 to lock the cane section 2 to the cane section 3 in its extended position, and against endwise movement in either direction. The cam heads 7 and 10 and the lock slots 8 and 11 are all vertically alined.

An annular cap 12 having depending peripheral hinge lugs 13 is detachably and rigidly secured to the outer end of the cane section 3 by means of a screw bolt 14. Folding cover supporting ribs are pivotally connected near their inner ends to the hinge lugs 13. As best shown in Figs. 1 and 2, these cover supporting ribs are each made up of an inner section 15, an intermediate section 16, and an outer section 17. The inner and intermediate sections 15 and 16 are connected by hinged joints 18, arranged to permit the rib sections 16 to be folded inward onto the rib sections 15, as best shown in Fig. 2. Hinged joints 19 connect the intermediate and outer rib sections 16 and 17 and are arranged to permit the rib sections 17 to be folded outward onto the intermediate rib sections 16, as best shown in Fig. 2. At their inner ends, the rib sections 17 terminate in stop fingers 20, arranged to engage the rib sections 16 and hold the outer rib sections 17 below dead centers, as best shown in Figs. 1 and 7, the purpose of which will presently appear.

A cover 21, of any suitable material, is stretched over the cap 12 and supporting ribs. This cover 21 is secured to the cap 12 by means of a washer 22 on the screw bolt 14, and its periphery is secured to the free ends of the rib sections 17 by stitching or otherwise. The drawing action of the cover 21 tends to hold the free ends of the rib sections 17 pulled downward. An annular flange 23 having a notched and grooved periphery is integrally formed on the inner end of the cane section 3. Folding stay rods 24, at their lower ends, are seated in the notches of the flange 23 and pivotally secured thereto by means of a wire band 25 seated in the groove of said flange. At their outer ends, the stay rods 24 are pivotally attached to the intermediate portions of the

- rib sections 16. The stay rods 24 are each made up of two sections connected by a hinge joint 26, arranged to permit the stay rods to fold inward, as best shown in Fig. 2.
- 5 Slidably mounted on the cane section 3 is a collar 27 having a notched and grooved periphery. Links 28 have their inner ends seated in the notches of the collar 27, and are pivotally attached thereto by means of 10 a wire band 29 seated in the groove of the collar. The outer ends of the links 28 are pivotally attached to the intermediate portions of the inner sections of the stay rods 24. A head block 30 is slidably mounted on 15 the cane section 2. Slidably mounted in perforations in the flange 23 is a pair of rods 31 rigidly secured at their upper ends to the sliding collar 27, and rigidly secured at their lower ends to the head block 30. A 20 spring pressed latch 32 is pivotally mounted on the head block 30 and is adapted to engage the flange 23 to hold the head block 30 interlocked with the cam section 2 when the umbrella is folded.
- 25 Stop flange 33 is spaced below the cap 12 and rigidly secured to the cane section 3. Slidably mounted on the cane section 3 between the cap 12 and the stop flange 33, is a sleeve 34 terminating at its lower end in 30 an outwardly extended flange 35, having a notched and grooved periphery, similar to the flange 23 and collar 27. The inner ends of the rib sections 15, beyond their pivotal connections are curved inward and downward 35 and are provided with segmental slots 36. The slotted ends of the rib sections 15 are mounted in the notches of the flange 35 and are loosely secured thereto by means of a wire band 37, mounted in the groove of said flange. These slotted ends of the rib sections 15 are adapted to engage the stop flange 33 and limit the opening movements 40 of the rib sections 15. Surrounding the sleeve 34 is a coiled spring 38 compressed between the cap 12 and the flange 35, tending 45 to hold the rib sections in engagement with said stop flange 33. A transversely extended pin 39 is rigidly secured to the sleeve 34 and works vertically in a pair of diametrically opposite slots 40 formed in 50 the cane section 3.
- The operation of the improved umbrella may be briefly stated as follows:—Normally, the spring latches 6 and 9 hold the sections 5 of the cane in their extended or operative positions, and the stay rods 24 and spring 38 hold the cover supporting ribs in their open positions.
- To close or hold the improved umbrella, 55 the head block 30 is first moved inward into engagement with the flange 23, and is locked thereto by means of the latch 32. This movement of the head block 30 through the several connections to the stay rods 24, first buckles said stay rods, then the rib sections 16 are folded inward onto the rib sections 15, and, at the same time, all of the rib sections are partly folded, as shown in Fig. 2. During the first process of positively folding the rib sections 15 and 16, the rib sections 17 are folded under the action of gravity toward the rib sections 16, also shown in Fig. 2.
- 16 After the head block 30 has been locked to the flange 23, the cam head 7 is pressed inward by the thumb and, at the same time, the cane section 1 is forced inward, thereby camming the head 7 out of the slot 8. Continuing the movement of the cane section 1, the inner end thereof engages the cam head 9 and forces the same outward into a position to be engaged by the inward movement of the cane section 2 and, thereby, forced completely out of the slot 11. The cane sections 1 and 2 are of substantially the same length and the continued inward movement of the cane section 1 carries therewith, by means of the hand piece 5, the cane section 2.
- 17 During the final inward movements of the cane sections 1 and 2, the cross pin 39 is engaged thereby and the connected sleeve 34 moved against the tension of the spring 38. This final movement of the cane sections 1 and 2 completes the folding movement of the umbrella. The latches 6 and 9 frictionally hold the cane sections 1 and 2 in their closed positions.
- What I claim is:
1. An umbrella comprising a cane, cover supporting ribs pivotally attached to said cane, a cap rigidly secured to said cane, outward of said supporting ribs, a sliding sleeve mounted on said cane and connected to said ribs inward of their pivotal connections, and a spring compressed between said sleeve and said cap, tending to hold said ribs extended.
  2. An umbrella comprising a cane, a cap and a stop flange spaced apart and secured to said cane, cover supporting ribs pivotally connected to said cap, a sleeve slidably mounted on said cane between said cap and stop flange and connected to said ribs inward of their pivotal connections, and a spring compressed between said cap and sleeve, tending to hold said ribs extended and in engagement with said stop flange.
  3. In a folding umbrella, the combination with a sectional cane, of cover supporting ribs made up of inner, intermediate and outer sections pivotally connected, said inner sections being pivotally connected to said cane, said intermediate sections arranged to be folded outward onto said inner sections, said outer sections arranged to be folded inward onto said intermediate sections, folding stay rods pivotally connecting said intermediate rib sections and said cane, extensions on said outer sections for holding the same below dead centers, and a cover

stretched over said ribs tending to pull the free ends of said outer ribs downward.

4. An umbrella comprising a cane made up of sections telescopically mounted, one within the other, cover supporting ribs pivotally connected to said cane, a sliding sleeve connecting said ribs inward of their pivotal connections and having a projection working in a slot formed in the outer cane section, and a spring tending to hold said ribs extended, the inner section of said cane arranged to engage the projection on said sleeve during its closing movement and positively fold said ribs against the tension of said spring.

5. In a folding umbrella, the combination with a cane made up of sections telescopically mounted, one within the other, of cover supporting ribs, comprising pivotally connected inner and outer sections, folding stay rods pivotally connecting said outer rib sections and the outer cane section, a sliding collar mounted in the inner cane section, links pivotally connecting said sliding collar and the lower sections of said stay rods, a sliding head on said inner cane section, a rigid connection between said sliding collar

and said sliding head, and a lock carried by said sliding head and engageable with said outer cane section for holding the umbrella closed.

6. In a folding umbrella, the combination with a cane made up of sections telescopically mounted, one within the other, of cover supporting ribs, comprising pivotally connected inner and outer sections, a projecting flange on the outer section of said cane, folding stay rods pivotally connecting the outer sections of said ribs and said flange, a collar slidably mounted on the inner section of said cane, links pivotally connecting the lower sections of said stay rods with said sliding collar, a head block slidably mounted on the inner section of said cane, a rod slidably mounted in said flange and rigidly connecting said sliding collar to said head block.

In testimony wherof I affix my signature in presence of two witnesses.

BROR ADOLPH NYGREN.
